UNITED STATES PATENT OFFICE.

EVAN THOMAS, OF ABERDARE, COUNTY OF GLAMORGAN, ENGLAND.

MINER'S LAMP.

SPECIFICATION forming part of Letters Patent No. 358,305, dated February 22, 1887.

Application filed May 11, 1886. Serial No. 201,792. (No model.) Patented in France March 9, 1886, No. 174,646, and in Belgium March 10, 1886, No. 72,299.

To all whom it may concern:

Be it known that I, EVAN THOMAS, a subject of the Queen of Great Britain and Ireland, and residing at Aberdare, in the county 5 of Glamorgan, Kingdom of Great Britain and Ireland, have invented new and useful Improvements in Miners' Safety-Lamps, (which have been patented to me in France, March 9, 1886 No. 174,646, and in Belgium March 10, 1886, No. 72,299,) of which the following is a specification.

This invention relates to miners' safety-lamps of the kind having a reticulated cylinder or cage surrounded by a metal outer casing or shield; and it consists in the combination, 15 with these, of guards or deflectors, as herein-after described, for the purpose of preventing the flame from being blown through the meshes of the wire-gauze by the force of a rush or powerful current of air or of gas, or 20 admixture of gas and air, to which such lamps are liable to be exposed.

The accompanying drawing shows a central vertical section. The lower part, including 25 the lamp proper, is of ordinary construction, which may be varied as may be desired.

a is the reticulated cylinder or cage, which may be of wire gauze, as usual, the upper portion being, in the example illustrated, doubled 30 in thickness by the addition of a reticulated cap, *a'*.

b is the outer casing or shield, which* may be of sheet metal and may be cylindrical, or conical, as shown. It is surmounted by an 35 overhanging cover, *b'*.

c and *e* are air-inlet holes.

d d are outlets for products of combustion and air.

f is a metal guard arranged around the lower 40 part of the reticulated cylinder or cage *a*, and extending upward a certain distance from the upper face of the ring *g*, which surmounts the glass *h*. This guard is made with a flange or projection, *f'*, that serves as a deflector. The 45 form of the guard may be modified by making it cup-shaped and open at the top, leaving an annular space between the wall of the cup and the exterior of the reticulated cylinder or cage *a*. Opposite the series of holes *e e* and spring- 50 ing from the inside of the shield is a ring-shaped guard, *i*, which is curved inward as it extends upward toward the cover of the shield, below which it terminates. It will be ob-

served that the holes *d* in the cover *b'* of the shield are in a plane which lies outside of the 55 edge of the top or mouth of the ring-shaped guard *i*.

Air to feed the flame passes into the interior of the lamp through the lower and upper holes, *c* and *e*, in the body of the shield. The 60 current, after entering the holes, impinges upon the lower and upper guards, which consequently intervene to break the force of currents that otherwise would be liable to cause the flame to be blown through the meshes of 65 the gauze, while products of combustion pass out through the perforations *d* formed, as aforesaid, in the cover of the shield. A downward current, passing in at the perforations *d* in the cover of the shield, would be deflected 70 by the upper guard, *i*, so as to pass out through the holes *e*.

What I claim is—

1. A bonneted chimney-lamp comprising, in combination, the lower lamp-standard, the 75 upper outer casing, *b b'*, the reticulated cylinder or cage *a a'*, the support *f'* for said cage, the chamber *f* below said cage, two or more guards, and the upper and lower inlets, substantially as described. 80

2. In a miner's safety-lamp, the combination, with a reticulated cylinder or cage, *a a'*, ring *g*, and an outer casing or shield, *b*, with lower and upper holes, *c* and *e*, of a guard, *f*, arranged around the lower part of said reticulated cylinder or cage *a*, extending upward a certain distance from the upper face of said ring *g*, and flanged or otherwise formed at its upper part so as to extend outward nearly to the inner surface of said outer casing or shield, 85 *b*, thereby serving as a deflector, substantially 90 as described.

3. In a miner's safety-lamp, the combination, with the ring *g*, of the reticulated cylinder or cage *a*, casing or shield *b*, with inlet holes *c* and *e*, cover *b'*, with holes *d*, guard *f*, with flange *f'*, and guard *i*, all arranged and operating substantially as described, for the purpose 95 specified.

EVAN THOMAS.
